GAS AND AIR MIXING APPARATUS

John J. Maxon, Muncie, Ind., assignor to Maxon
Premix Burner Company, Muncie, Ind., a cor-
poration of Delaware

Application July 5, 1933, Serial No. 679,095

4 Claims. (Cl. 48—188)

This invention relates to improvements in apparatus wherein a complete mixture of combustible gas and air is obtained mechanically, and wherein a complete combustion of the mixture begins immediately upon its passing from the burner conduit into the combustion chamber.

An apparatus of the above description, and as illustrated in United States Letters Patent issued April 9, 1918 to Harry R. Maxon, No. 1,262,078, 10 comprises a fan adapted and arranged to receive air at substantially atmospheric pressure, an unobstructed delivery conduit leading from the fan, a damper for regulating the quantity of air admitted to the fan casing, a pipe for supply of fuel 15 gas directly to the fan casing, and a valve for regulating the gas supply from said pipe.

In an apparatus of the above description, a characteristic of the operation of the fan is that there is variation in the suction force of the fan 20 coincidentally with variation of the area of the opening admitting air to the fan. Also it is a characteristic of the operation of furnaces that incident to peculiarities of form, nature and construction, and of draught, currents and pressures, 25 a fixed or unchanged ratio of gas and air in the fuel mixture is ineffective. In practice it has been ascertained that in the absence of means to modify the variation of inflow of gas, to compensate for the effect produced on the mixture by 30 the said change in suction force, and by conditions in the combustion chamber, there is an indefinite and inefficient proportioning of the air and gas.

Accordingly, my invention has for its object the 35 providing, in combination with the fan casing, of means consisting of a damper to vary the amount of air to be admitted, a valve to vary the amount of gas to be admitted, and means cooperating with the damper and the valve, 40 whereby a variation of the inflow of gas, with relation to the air inflow, and modification of the 45 said variation may be automatically had and maintained at the different stages of operation of the damper between its two extreme positions.

Further and more specific aims of the invention 45 are to provide a mechanism therefor that is economical of construction and manufacture, and which is durable and dependable.

The above named objects, as well as other purposes 50 which will appear as the specification of my invention proceeds, are accomplished by, and my invention is exemplified in the preferred form of embodiment which is described in the following specification and is illustrated in the accompanying drawings,

Suitable characters of reference identify the several parts of the invention as they appear in the different views in the drawings, in which—

Figure 1 is a side view of my invention, a portion of the fan casing, and a portion of the entry 5 box being broken away.

Figure 2 is a front view, taken in the direction of arrow 4 in Figure 1.

Figure 3 is a top plan view of Figure 2.

Figure 4 is a vertical cross section view on the 10 line 4—4 as seen in the direction of arrow 4 in Figure 1.

Figure 5 is a vertical cross section view on the line 5—5 as seen in the direction of arrow 4 in 15 Figure 1.

Figure 6 is a detached cross section detail view taken on the line 6—6 in Figure 4, enlarged.

Figure 7 is an enlarged vertical central longitudinal sectional view on the line 7—7, in the direction of arrow 7 in Figure 3.

Figure 8 is a front view of Figure 7, the cam carrier member being partly broken away.

Figure 9 is a rear view of Figure 8, a portion of the disk-shaped damper plate being broken away.

Figure 10 is a top plan view of Figure 8.

Figure 11 is a vertical cross section view on the line 11—11 in Figure 7.

Figure 12 is a front view of the invention taken in the direction of arrow 4 in Figure 1, there being embodied in this view in Figure 12, a modification 30 whereby the damper may be operated by mechanical means.

The fan casing A and fan wheel B are of usual construction, the casing having a central opening C through which the air and gas are admitted. 35 Conduit D which is attached to the discharge mouth of the casing, extends to the burner (not shown). At the said opening C, I provide a chamber like receptacle which I designate as an entry box 1. This entry box communicates at its 40 open side 2 with the opening C of the fan casing. Provided in the opposite side 3 of said box, are spaced segmental air inlets 4. A plate 5 which is secured by suitable cap screws constitutes a closure of the bottom of the entry box, and it also 45 constitutes the base of a housing 6. In a threaded aperture in said plate 5 is secured a fuel gas supply pipe 5a. A fluted flanged valve head 8 which is retained loosely in a bore in the rear wall of said housing and is seated as at 9 has a stem 50 10 that is received in the central bore of an abutment head 11. This abutment head is screwed to securely sealed position in the front wall of said housing. A helical spring 12 whose one end bears against the shank of said abutment head, 55

has its other end bearing against the said valve head 8, the latter being thereby retained yieldingly in its position, as shown in Figure 7.

Pivottally fulcrumed on a supporting post 14, is 5 a lever 15 whose lower and rounded end 16 impinges against the face of the valve head 8. The power arm of said lever has the rounded face 16a. Slidingly retained in the longitudinal bore of a bushing 17 that is securely seated in a bore 18 10 of a lug provided on the interior of the box wall, is a push rod 20. This push rod made preferably of non-corrosive material, is of such length that with its inner end at engagement with the face 16a of the said lever, its other end extends beyond the 15 face of the entry box.

Retained loosely in the said bore 18, is a ring 20 made of fiber or other suitable material, and which I designate as a brake member 21. A helical spring 22 which is disposed within said bore 18 urges the said brake member forwardly as indicated in Figure 6. The function of this brake member will be presently referred to.

A shaft 24 which is secured to and which projects from the wall 3 of the entry box is threaded 25 at its end, and it supports the parts to be presently referred to.

A device which I designate as a damper, consists of a metal disk 26 having its rear face machined to bear directly in engagement with the 30 machined front face of the wall 3 of the entry box. In this disk are provided spaced portways 27 which correspond in shape and dimension with the air inlets 4 of the entry box, and an arcuate slot 28 positioned between said portways is so 35 spaced from the center of the disk that the end portion of the push rod 20 is received therein. The said disk, provided with a suitable boxing 29 is journaled on the shaft 24, as shown in Figure 7. At the top surface of the entry box, as shown 40 in Figures 3 and 10, and spaced from right to left, are index characters which may be designated as stations 7, 6, 5, 4, 3, 2, 1, and 0. An index tooth finger 30 on the peripheral face of the disk 26 is so positioned with reference to the 45 portways 27 that when they are in registration with the air inlets 4, as shown in Figure 2, the said finger 30 is in registration with the station 7.

In a shallow recess 31 provided therefor at the rear side of said disk, (see Figure 9) an arcuate strip 32 of resilient material, preferably strip steel, has its shank portion secured to said disk as by cap screws 33. This strip is of a length to span the slot 28 and its urge is toward the front face of the disk. Projecting from the front of the disk, and spaced from the hub thereof, as shown in Figures 7 and 8, is a stud 34. A segmental carrier plate 35 provided with an aperture in which the said stud 34 is received, is secured to the said disk by means such as cap screws 36.

On a curve having a radius the same as the slot 28, threaded adjusting pins 38 are arranged in successive order, as shown in Figures 2 and 8, and they are designated by numerals, reading right to left, namely 0, 1, 2, 3, 4, 5, 6, and 7. Each 55 of these pins is individually adjustable by the use of a suitable implement such as a screw driver. The adjusting of these threaded pins being toward or from the cam strip 32, the outside boundary line of the said cam strip, accordingly is defined, and it is determined by the positions to which these several individual pins are adjusted. Against the said cam strip 32, the 60 push rod 20 impinges, and to which further reference will presently be made.

To facilitate the moving of the said disk I pro-

vide a crank 40 whose body portion 41, provided with a suitable flanged boxing 42, is journaled on the shaft 24. In the said body portion 41 is a recess 43 in which the stud 34 is received. By a binding nut 45 and washer 46, the said crank and the aforesaid disk are retained in operative position on the shaft 24, as shown in Figure 7. The length of the push rod 20 is such that when the disk is in the position shown, the portways 27 of said disk being in registration with the air inlets 4 and the indicating finger 30 being in registration with station 7, see Figure 7, the gas valve 8 is in the open position. Pressure of the spring 22 against the brake member 21 holds the latter firmly against the rear surface of the disk 26, 15 thereby holding the disk against becoming dislodged from any of the positions to which it may be set.

For the maintaining of a fuel mixture that is of proper consistency for the demands due to 20 different furnace capacities, conditions, and requirements, my invention is entirely effective. In the set-up shown herein, air inlets 4 are wide open when the index finger 30 is at "7" station. Gas valve 8 is in open position. By the pressure 25 of spring 42, transmitted through valve head 8, and lever 15, to push rod 20, the latter is urged in the direction of arrow in Figure 7, and it is held impinged against the cam strip 32.

Preliminary to operating the apparatus, the 30 arm 40 is moved in the direction of arrow "Off" the index finger 30 being brought to registration with station 0. The air inlets 4 now are closed. The pin 0 is now in such position that the valve 8 is in closed position. Arm 40 is now 35 moved in the direction of arrow "On", bringing index finger 30 to station 1. The fan is put into operation. Pin 1 is then adjusted so as to afford the desired measure of opening at valve 8. When 40 tests at the furnace (not shown) indicate that the proper amount of gas has been obtained with relation to the amount of air admitted by the air inlet 4 (at the stage wherein finger 30 is at station 1) the arm 40 is again moved in the direction of arrow "On", bringing the index finger 30 45 to station 2. Pin 2 is then adjusted so as to afford the desired measure of opening at valve 8. When 50 tests at the furnace show that the proper ratio of gas to the air as admitted by the air inlet 4 is had, (at stage wherein finger 30 is at station 2), the arm 40 is again moved in the direction of arrow "On", the finger 30 passing from station 2 to station 3. Pin 3 is then adjusted as above described, and in the further successive movement 55 of the disk, its index finger is at the stations 3 to 55 4, 4 to 5, 5 to 6, and 6 to 7, and pins 3, 4, 5, 6, and 7, are adjusted as above described.

It will be understood that after the several pins 38 have been adjusted as aforesaid, the contour line of the cam strip 32 is subject to variations 60 in degree accordingly. It is for the reason that the amount of gas required, with relation to the amount of air admitted, must be modified in conformity with the demands incident to arbitrary requirements at the furnace, that I have provided 65 the cam which is capable of being made into contour necessary to obtain variation of the position of the valve head 8.

It will be understood that by the pressure of 70 spring 42, the push rod 20 is at all times impinged against the face of the cam strip, and that the action of the latter, in causing the valve head to function when the said disk is moved, is positive, direct, and dependable.

By my invention and its operation as above de- 75

scribed, it is possible to obtain an air and fuel gas mixture wherein there is a modification of the variation of the amount of fuel gas, with relation to the amount of air being admitted to the fan, at each of the several stations at which the index finger 30 of the damper is set during the operating of the damper from the completely off position to the completely on position.

Another advantage of my invention is, that it lends itself to efficient use in instances where it is desired that the damper may be operated by mechanical means. For an installation intended as above, no change is made, except that a crank member of the construction, as shown in Figure 15 12, and designated by the numeral 50, is substituted for the crank member 40. In the body portion 51 of this crank 50, are opposed spaced concentric slots 52, in which are retained knuckle studs 53 and 54 which are capable of being made 20 fast at desired different adjusted positions in said slots.

For example, the damper is to be so operated that its cycle will be only between the station 0 and the station 4. The said studs 53 and 54 are 25 so positioned, that with the indicator finger 30, at station 4, the arm 50 is at the lowermost point of its stroke. Now with the swing upwardly of the said arm 50, the hub or body portion 51 idles until knuckle 53 meets the stud 34 and thence 30 the carrier member 35 and the cam 32 is moved in the direction of the arrow marked "Off", until finger 30 meets the station 0 (the top limit of the stroke of said arm 50). As the arm 50 returns to lower position, the knuckle 53 leaves stud 34 35 and later, the knuckle 54 meeting the stud 34 carries the cam in the reverse direction and to its original position, namely station 4. Means for mechanically actuating the arm 50, as above described, may consist of an electric motor 56 40 which is mounted upon the entry box 1. Power transmitting connections may consist of the crank 51, and the connecting rod 58, one revolution of the said crank 57 imparting to the arm 50 a raising and lowering motion.

45 In the embodiment of my invention as it is illustrated herein, the amount of machine work involved is relatively small, the different parts are capable of being economically assembled, and the apparatus in its entirety is close-built and 50 substantial, and not liable to become deranged or to get out of order. Access may be readily had to the interior thereof when necessary for inspection, or for renewals, and the device throughout is capable of being adjusted to meet the most 55 exacting conditions that may be imposed.

It will be understood that modifications may be made in details of construction, form, and arrangement of the several parts, within the scope of the invention as it is defined in the appended 60 claims, without departing from the spirit of the invention or sacrificing any of its advantages.

What I claim as my invention, is—

1. A gas mixing apparatus, comprising a fan whose casing is provided with an air inlet, an 65 entry box having air inlets, and an open side

thereof communicating with the air inlet of the fan, a valve in the said entry box and which is retained yieldingly in closed position, a fuel gas supply pipe to said valve, a damper adapted to vary the area of said entry box air inlets, a 5 push rod mechanism adapted to move the aforesaid valve to open position, a resilient cam strip carried by the damper and in engagement with said push rod mechanism, and spaced pins on said damper and in registration with said cam 10 strip and which are individually adjustable to modify the outside boundary line of said cam strip.

2. A gas mixing apparatus comprising a fan whose casing is provided with an air inlet open- 15 ing, an entry box having an open side communicating with said air inlet opening and having air inlets through its opposite side, a valve in said entry box and which is retained yieldingly in closed position, a fuel-gas supply pipe 20 connected to said valve, a damper movable rotatively to vary the area of said air inlets, means to move said valve to open position, and a cam carried by said damper to actuate said valve moving means, the said cam being capable of ad- 25 justment whereby the degree of opening and closing of the gas valve is varied in conformity with the degree of opening and closing of the said air inlets during all stages of operating the damper from the fully open, to the completely 30 closed position.

3. A gas mixing apparatus comprising a fan whose casing is provided with an air inlet opening, an entry box having an open side communica- 35 ting with said air inlet opening and having air inlets through its opposite side, a valve in said entry box and which is retained yieldingly in closed position, a fuel-gas supply pipe connected to said valve, a disk-shaped damper movable rotatively to vary the area of said air inlet, and 40 a cam carried by said damper to actuate the said valve moving means, the said cam being capable of modification at different stages of the cycle of operating of the damper between its extreme po- 45 sitions.

4. A gas mixing apparatus comprising a fan whose casing is provided with an air inlet, an entry box having an open side communicating with said air inlet and having air inlets entering same, a valve in said box and which is retained yieldingly in closed position, a fuel-gas supply pipe 50 connected to said valve, a disk-shaped damper movable rotatively to vary the area of said air inlets, a push rod mechanism in the entry box 55 and which is operable to move said valve to open position, a resilient cam strip carried by the damper and in engagement with said push rod mechanism, and spaced pins arranged on said damper and in registration with said cam, and 60 which are adjustable to modify the outside boundary line of said cam strip at the different stages of the movement of the damper between its extreme positions.

JOHN J. MAXON. 65
